UNITED STATES PATENT OFFICE

95,101

DESIGN FOR A KITE PLANE GLIDER OR SIMILAR ARTICLE

Ulmont B. Williams, Miami, Fla.

Application February 1, 1935, Serial No. 55,200

Term of patent 14 years

To all whom it may concern:

Be it known that I, Ulmont B. Williams, a citizen of the United States, residing at Miami, in the county of Dade and State of Florida, have invented a new, original, and ornamental Design for a Kite Plane Glider or Similar Article, of which the following is a specification, reference being had to the accompanying drawing, forming part thereof.

In the drawing:

Fig. 1 is a perspective view of a kite plane glider or similar article, showing my new design.

Fig. 2 is a view in front elevation of the same.

I claim:

The ornamental design for a kite plane glider or similar article as shown.

ULMONT B. WILLIAMS.
